W. R. FOWLER.

VACUUM CLEANER.

APPLICATION FILED OCT. 26, 1911.

1,027,117.

Patented May 21, 1912.

UNITED STATES PATENT OFFICE.

WILLIAM R. FOWLER, OF BALTIMORE, MARYLAND.

VACUUM-CLEANER.

1,027,117.

Specification of Letters Patent.

Patented May 21, 1912.

Application filed October 26, 1911. Serial No. 656,920.

To all whom it may concern:

Be it known that I, WILLIAM R. FOWLER, a citizen of the United States, residing at Baltimore, in the State of Maryland, have invented certain new and useful Improvements in Vacuum-Cleaners, of which the following is a specification.

This invention relates to an improved vacuum dust remover for use on floors and carpets.

One object of the invention is to provide a vacuum-operating apparatus that may be operated entirely by hand.

The invention is illustrated in the accompanying drawing, in which,

Figure 1 is a side view of the apparatus showing all parts in position for operation, and also showing that at such time the handle rod has a raised inclined position. Fig. 2 is a vertical longitudinal section, showing the inner cylinder partly drawn out; this figure is on a larger scale. Fig. 3 is a cross section of the inner reciprocable cylinder on the line 3—3 of Fig. 2. Fig. 4 is a front end or nozzle-end view of the inner cylinder. Fig. 5 is a perspective front-end view of part of the inner cylinder and nozzle, showing the nozzle-pipe broken, and the swinging hook that engages the nozzle-pipe.

The main parts of the apparatus comprise an exterior cylinder, A, which has a horizontal position; an interior cylinder, B, that fits telescopically within the said exterior cylinder and is movable therein like a piston; a tubular-shaped dust-receptacle, C, made of textile or similar fabric and carried within the said interior cylinder, B; a foot-piece, D, flexibly attached to the exterior cylinder at its rear end and a suitable handle-rod, E attached to the outermost or front end of the reciprocable interior cylinder.

The outer cylinder, A, has an opening, f, in its rear end, and a suitable valve, g, closes said opening when the piston-cylinder, B, moves outward. A suitable screen, h, on the rear end of the outer cylinder, A, covers the valve-opening and protects the valve. The foot-piece, D, rests on the floor and permits the operator to place his foot therein, as indicated in Fig. 1, and by bearing his weight on the said foot-piece he may hold the rear end of the outer cylinder, A, from movement while the inner cylinder, B,

is being reciprocated. The foot-piece has two joints, k, l, that attach it to the outer cylinder and these joints provide for either a sidewise movement, or an up and down movement. The rear end of the inner cylinder, B, is also provided with a port, i, that is opened by a valve, j, when this cylinder moves outward but said port is closed by the valve when the cylinder, B, moves back into the outer cylinder, A. The movements, back and forward, of the inner cylinder, B, are effected by the manual operation of a person who has grasped the rod-handle, E, and either pulls or pushes thereon.

The rod-handle has an end attached to the front end of the inner cylinder, B, by means of a joint, m; this permits the handle, E, to be raised on an inclined position, as seen in Fig. 1, or allows it to be lowered to a horizontal position, and rest on handle-support device, n, as indicated in Fig. 1 in broken lines.

The reciprocable cylinder, B, is provided with an outside guide-rod, o, that extends longitudinally with respect to said cylinder and is attached to the front end thereof by a bolt or pin, p, so that said guide rod may extend along outside of the main cylinder, A, which latter is provided with two bearings, q, through which said rod may slide whenever any movement takes place of the inner cylinder, B. The inner cylinder in the present instance, is also provided on the exterior of its bottom with another rod, r, which extends longitudinally and has bearing in a notch formed in a short plate, r¹, fixed at the open and front end of the outer cylinder, see Figs. 2 and 5. When the inner cylinder makes any movement, either inward or outward the rod, r, slides on the said notched plate, r¹. The outer cylinder at or near its front open end has a suitable foot, s, to rest on the floor and support this cylinder.

A suitable packing ring, u, is around the inner cylinder, B, and fits in contact with the inner surface of the outer cylinder, A, and serves as an ordinary piston packing when the inner cylinder reciprocates.

The front end of the inner cylinder is closed by a head, v, and a cross-bar, v¹, has its ends engaging two catches, v², secured on the side of said cylinder, and this cross-bar thereby holds the head, v, in position. Any

additional fastening may be used to confine the head in its place. The inner cylinder also has casters or rollers, *t*, at its front end to support said end; the rollers travel on the 5 floor.

The nozzle, *w*, of suitable shape, is carried at the front end of the reciprocable cylinder, *B*; it is open at its bottom, and like all nozzles of vacuum cleaners this nozzle 10 must be in contact with the surface of the carpet or floor when the nozzle is moving. The nozzle has a pipe, *w*¹, that opens through the head, *v*, of the inner cylinder and discharges into the dust receptacle, *C*; it will 15 be seen that when the inner cylinder, *B*, moves outward or extends and thereby the vacuum is produced, the suction will cause the dust on the carpet to enter the nozzle, *w*, and such dust will then pass through the 20 pipe, *w*¹, into the duct receptacle *C*. In order to brace the nozzle, and hold it firmly to its position at the rear end of the reciprocable cylinder, a bracket plate, *x*, is rigidly secured to the said head, *v*; this bracket carries a swinging hook, *y*, which is half-circular and has one end pivoted or jointed by a pin, *y*¹, to said bracket plate, *x*; the free end of the hook, *y*, has a hole that engages a pin, *z*, on the bracket plate. This swinging hook takes about the nozzle-pipe, *w*¹, and the latter is clamped between the edge 25 of the bracket, *x*, and the hook, *y*, and firmly held.

In the description thus far given the operation has been partly set forth. To further explain, it may be stated that at beginning the dust-bag, *C*, is in a collapsed condition. A person places his right foot in the foot-piece, *D*, and bears his weight on 30 same; this serves to hold the outer cylinder *A*, stationary. Then with both hands the person grasps the handle, *E*, and shoves it forward in a direction away from the foot-piece. This shoving forward of handle, *E*, 35 while the foot-piece, *D*, holds the outer cylinder, *A*, stationary and keeps it from moving, causes the interior cylinder, *B*, to be extended or projected by a telescopic movement. This action produces a vacuum in the 40 outer cylinder, *A*, and thereby dust on the floor or carpet is sucked into the nozzle, *w*, and drawn into the fabric dust-receptacle or bag, *C*; during the projected movement of cylinder, *B*, the valve, *j*, opens and the 45 valve, *g*, remains closed. Now the operator pulls on handle, *E*, and this causes the interior cylinder, *B*, to be drawn back into the cylinder, *A*; valves then change position—valve *j*, closes and valve, *g*, opens, the dusty air is 50

filtered in bag, *C*, and the clean filtered air 50 discharges at the valve, *g*, into the room.

Having thus described my invention what I claim and desire to secure by Letters Patent is,—

1. In a vacuum cleaner the combination of 65 an outer cylinder in a horizontal position having one end closed and provided with a valve; a foot-piece to rest on the floor and flexibly attached at the closed end of said outer cylinder; an interior cylinder fitting 70 like a piston within the outer cylinder and reciprocable therein; a flexible bag-shaped dust collector in said interior cylinder; an inlet-nozzle carried at the outermost end of 75 said interior cylinder and adapted to contact with the surface of the floor as said cylinder reciprocates; and an actuating rod-handle attached to the outermost end of said reciprocable cylinder.

2. In a vacuum cleaner the combination of 80 an outer cylinder working in a horizontal position and having a closed end provided with a valve; a foot-piece that rests on the floor and is connected with the said outer cylinder by two joints one of which permits a sidewise movement and the other a vertical movement; a second cylinder fitting like 85 a piston and also movable in said outer cylinder and provided at its outermost end with rollers that travel on the floor; a dust collector carried in the said movable cylinder; and an inlet nozzle carried at the outermost end of 90 said movable cylinder and discharging into the dust-collector and contacting with the surface of the floor.

3. In a vacuum cleaner the combination of 95 two cylinders one fitting like a piston within the other and to be operated in a horizontal position and one reciprocable relative to the other which remains stationary; a foot-piece attached to one of said cylinders and arranged to rest on the floor to enable the operator to hold it from movement by the pressure of his foot; an actuating rod-handle attached to the other cylinder and by 100 means of which the same operator may impart thereto reciprocating movement; a flexible dust-collector attached to one cylinder, and an inlet nozzle to contact with the surface of the floor and carried by the reciprocable cylinder and discharging into the 105 said dust-collector.

In testimony whereof I affix my signature in presence of two witnesses.

WILLIAM R. FOWLER.
